ABSTRACT: There is disclosed in an alarm system, a supervisory signal monitoring circuit for providing an indication of a disruption in the system and comprising supervisory conductor means for normally carrying a supervisory current, termination circuit means coupled to the supervisory conductor means, and a trouble indicating circuit coupled to the supervisory conductor means. The trouble indicating circuit includes an oscillator circuit having first circuit means for developing an oscillating signal and second circuit means for applying the oscillating signal to the supervisory conductor means to thereby cause a supervisory current to flow through the conductor means, resistive means coupled to the supervisory conductor means for developing a control signal in response to the flow of the supervisory current, trouble indicating means, and signal responsive circuit means coupled to the control signal developing means in response to the absence of the control signal to thereby provide an indication of a disruption in the supervisory conductor means.

ALARM CIRCUIT SUPERVISORY MEANS

BACKGROUND OF THE INVENTION

This application pertains to the art of electrical supervisory and monitoring circuits, and, more particularly, to circuits for monitoring the continuity of an electrical circuit and providing an indication of a disruption therein.

The invention is particularly applicable to alarm systems, such as industrial fire alarm systems, and will be described with particular reference thereto, although it will be appreciated that the invention has broader applications, such as, for example, in industrial electrical lighting systems, electronic control systems, etcetera.

The need for supervision of certain electrical circuits, such as alarm circuits, in order to provide an indication of a disruption in the continuity of the circuit, has long been recognized. Various techniques have heretofore been employed to provide the necessary supervision of alarm circuits. One such technique includes a circuit configuration in which a plurality of fire alarm indication means, such as alarm bells, are connected in series with a voltage supply source. Also connected in series with the series-connected alarm bells is an electromechanical relay, which, upon an interruption of the electrical continuity of the series circuit, is actuated to thereby energize a trouble indicating buzzer indicative of the circuit interruption. Generally, the relay is maintained in an energized condition by a small supervisory current flowing through the series circuit until such time as an interruption occurs in the circuit. In a series-connected circuit such as that described, the addition or removal of one or more alarm devices requires that compensating adjustments be made elsewhere in the circuit in order to maintain the requisite value of supervisory current. In addition, in a series-connected system of this type, the failure of even a single alarm device to operate when the system is actuated, causes the entire system to fail to operate.

Another technique heretofore employed to provide supervision of an alarm system is a circuit comprised of a plurality of alarm indicating means connected in parallel across a direct-current voltage supply source. Switch means are employed in the alarm system to change the effective polarity of the direct-current voltage source, which in turn causes the direction of current flowing within the alarm circuit to change from a normal condition to an alarm condition. This system also includes a plurality of polarity sensing means, such as diodes, connected in series with each of the alarm indicating means so that a current is allowed to flow through the alarm indicating means when the switch means is in the alarm position, and prevented from flowing through the alarm indicating means when the switch means is in normal position. In addition, a relay is connected in the parallel circuit with the switch means in a manner so that the relay is energized whenever continuity is maintained in the parallel circuit. The U.S. Pat. No. 3,309,685, to D. Manning entitled "Supervisory Circuit," and issued on Mar. 14, 1967, discloses such a supervisory circuit. The main disadvantage of such a supervisory circuit is that a relatively large power supply must be employed to convert the alternating-current line voltage to a direct-current voltage for energizing the supervisory circuit. In addition, only direct-current type alarm indicating means may be utilized in such a system.

SUMMARY OF THE INVENTION

The present invention discloses a new and improved supervisory circuit which overcomes all of the above referred to problems, and others, and provides a supervisory circuit which is simple in construction and dependable in operation.

In accordance with one aspect of the present invention, there is provided an alarm system comprising a remote station monitoring circuit including actuatable means, for upon actuation, transmitting an alarm signal indicative of an alarm condition at the remote station; alarm circuit means electri-

cally connected to the remote station monitoring circuit. The alarm circuit includes alarm indicating means and first circuit means for energizing the alarm indicating means in response to an alarm signal, resonant circuit means coupled to said first circuit means for normally carrying a supervisory current, and a supervisory circuit coupled to the first circuit means. In addition, the supervisory circuit includes an oscillator circuit having second circuit means for developing an oscillating signal to the first circuit means to thereby cause the supervisory current to flow through the first circuit means, resistive means coupled to the first circuit means for developing a control signal in response to the absence of the flow of a supervisory current resulting from a disruption in the electrical connection between the alarm circuit means and the monitoring circuit, trouble indicating means, and signal responsive circuit means coupled to the control signal developing means for energizing the trouble indicating means in response to the receipt of a control signal to thereby provide an indication of a disruption in the electrical connection between the alarm circuit means and the monitoring circuit.

In accordance with another aspect of the present invention there is provided a supervisory signal monitoring system for providing an indication of a disruption in the system and comprising supervisory conductor means for normally carrying a supervisory current, termination circuit means coupled to the supervisory conductor means, and a trouble indicating circuit coupled to the supervisory conductor means. The trouble indicating circuit includes an oscillator circuit having first circuit means for developing an oscillating signal and second circuit means for applying the oscillating signal to the supervisory conductor means to thereby cause a supervisory current to flow through the conductor means, resistive means coupled to the supervisory conductor means for developing a control signal in response to the flow of the supervisory current, trouble indicating means, and signal responsive circuit means coupled to the control signal developing means for energizing the trouble indicating means in response to the absence of the control signal to thereby provide an indication of a disruption in the supervisory conductor means.

In accordance with a more limited aspect of the present invention, the termination circuit means is comprised of a capacitive and/or an inductive circuit element.

In accordance with a still more limited aspect of the present invention, the termination circuit means is comprised of a capacitive element connected in series with an inductive element wherein the series connected elements are connected in parallel with the alarm indicating means.

In accordance with another aspect of the present invention, the termination circuit means is a resonant circuit means and includes a capacitive and an inductive element.

The principle object of the present invention is to provide a supervisory circuit which is responsive to the absence of a supervisory current for providing an indication of a disruption in an electrical circuit.

Another object of the present invention is to provide a supervisory circuit which is responsive to a supervisory current for, upon the absence of the supervisory current, energizing a trouble indicating means, such as a trouble buzzer or bell.

A further object of the present invention is to provide a supervisory signal monitoring circuit which eliminates current compensating resistors in the alarm circuit to thereby eliminate the adjustment of these compensating resistors, and the readjustment of these resistors whenever alarm indicating devices are added to or removed from the system.

A still further object of the present invention is to provide an alarm supervisory circuit in which either direct current or alternating current type alarm indicating devices may be employed.

A still further object of the present invention is to provide a supervisory signal monitoring circuit which employs an oscillating current supervisory signal for detecting a disruption in the supervisory circuit.

BRIEF DESCRIPTION OF THE DRAWINGS

These and other objects and advantages of the invention will become apparent from the following description of the preferred embodiments of the invention as read in connection with the accompanying drawings in which:

FIG. 1 is a schematic circuit diagram illustrating the preferred embodiment of the invention in conjunction with the alarm system; and,

FIG. 2 is a schematic circuit diagram of a second aspect of the present invention.

DESCRIPTION OF THE PREFERRED EMBODIMENT

Referring now to the drawings wherein the showings are for purposes of illustrating a preferred embodiment of the invention and not for purposes of limiting same, FIG. 1 illustrates the supervisory signal monitoring circuit employed in conjunction with an alarm system, and generally comprises an alternating-current voltage supply source V-1 connected to an alarm circuit AC and a supervisory monitoring circuit S. Supervisory monitoring circuit S is generally comprised of a power supply circuit PS, an oscillator circuit O, and sensing network SN.

More particularly, one of the terminals of voltage supply source V-1, which preferably takes the form of an alternating-current line source, is connected through a normally open switch S-1 to one of the terminals 1 of one of the sets of contacts 10 of an alarm relay RC. The other terminal of voltage supply source V-1 is connected directly to one of the terminals 2 of the other set of contacts 12 of alarm relay RC. The two sets of relay contacts 10, 12 of alarm relay RC generally take the configuration of a double-pole, double-throw switch which is actuated by a relay coil RC-C. Relay coil RC-C of alarm relay RC is connected in series with a normally open alarm actuator A and a voltage supply source V-2, which preferably takes the form of a direct-current voltage source.

Relay contacts 10 and 12 respectively include a pair of movable contacts 5 and 6, which are respectively connected to a pair of lines L-1 and L-2 of alarm circuit AC. Connected in parallel, and across lines L-1 and L-2 of the alarm circuit AC, are a pair of alarm bells A-1 and A-2, and a resonant network RN. As is readily apparent, alarm bells A-1 and A-2 may take the form of various alarm indicating devices, such as bells, lamps, buzzers, etc. In addition, while only two alarm bells A-1 and A-2 are illustrated in the preferred embodiment, it is contemplated that any number of such devices could be connected across lines L-1 and L-2 of alarm circuit AC. Preferably, the impedance of each alarm device is relatively high in comparison to the impedance exhibited by resonant network RN as will be discussed hereinafter. Resonant network RN is comprised of an inductive element 14 connected in parallel with a capacitive element 16 across lines L-1 and L-2 of alarm circuit AC. In the preferred embodiment of the present invention, inductor 14 and capacitor 16 are of the fixed type; however, it is contemplated that either one or both of these elements could be made variable in order to vary the resonant frequency exhibited by resonant network RN.

Terminals 1 and 2 of relay contacts 10 and 12 are respectively connected to a common ground connection and to the anode of a diode 18 in power supply circuit PS. The cathode of diode 18 is connected through a pair of series-connected resistors 20 and 22 to an output terminal 24 of power supply circuit PS. The junction point between resistors 20 and 22 is connected through a capacitor 26 to ground, and the output terminal 24 of power supply circuit PS is connected through a Zener diode 28, poled as shown in FIG. 1, to ground.

The output terminal 24 of power supply circuit PS is connected through a pair of series-connected resistors 30 and 32 in oscillator circuit O to ground. The junction point between series-connected resistors 30 and 32 is connected to the base of a PNP transistor 34 having its emitter connected through a

resistor 36 to the output terminal 24 of power supply circuit PS. The emitter of transistor 34 is also connected through a capacitor 38 to the output terminal 24 of power supply circuit PS, and the collector of this transistor is connected through a resistor 40 to ground. Also, the collector of transistor 34 is connected through three series connected capacitors 32, 44 and 46 to the base of this transistor. The junction point between capacitors 42 and 44 is connected through a series-connected variable resistor 48 and fixed resistor 50 to output terminal 24 of power supply circuit PS. Similarly, the junction point between capacitors 44 and 46 is connected through a series-connected variable resistor 52 and fixed resistor 54 to output terminal 24 of power supply circuit PS. Variable resistors 48 and 52 are preferably connected in common so that the impedances of these resistors 48 and 52 may be varied in common.

The collector of transistor 34 is also connected directly to the base of an NPN transistor 55 having its collector connected directly to output terminal 24 of power supply circuit PS, and its emitter connected through a resistor 57 to ground. The emitter of transistor 55 is also connected through a capacitor 56 to a third terminal of relay contact 10 of alarm relay RC. A third contact 4 of relay contact 12 of alarm relay RC is connected through a variable resistor 60 to ground, and is also connected through a series-connected resistor 62 and capacitor 64 to the base of an NPN transistor 66. Also, the base of transistor 66 is connected through a resistor 68 to ground, and the emitter of this transistor is connected through a pair of series-connected diodes 70 and 72, poled as shown in FIG. 1, to ground. Connected to the collector of transistor 66 is one terminal of a relay coil TR-C of trouble relay TR. The other terminal of coil TR-C is connected directly to output terminal 24 of power supply circuit PS. Also, connected to the collector of transistor 66 is one terminal of a capacitor 74 having the other terminal thereof connected to output terminal 24 of power supply circuit PS. Trouble relay TR also includes a pair of normally closed relay contacts TR-1 which are connected in series with a trouble buzzer TB and a direct-current voltage supply source V-3.

OPERATION OF PREFERRED EMBODIMENT

Upon closure of normally open switch S1, an alternating current signal is applied to terminals 1 and 2 of relay contacts 10 and 12 of alarm relay RC. Also, the alternating current signal is applied through power supply circuit PS to provide a constant direct-current output signal at output terminal 24 of power supply circuit PS. Zener diode 28 of power supply circuit PS serves as a voltage regulator for maintaining a relatively constant voltage direct-current signal at output terminal 24. This direct-current output signal is applied to oscillator circuit O which is generally comprised of an amplifier circuit including transistor 34 and its associated circuitry, and a phase shift network including capacitors 42, 44, and 46, and resistors 48, 50, 52, and 54. Oscillator circuit O operates in a manner similar to conventional phase shift oscillators in that the amplifier circuit provides a phase shift of 180°, and the phase shift network provides an additional phase shift of 180°, which is in turn fed back to the input circuit of the amplifier circuit, i.e., the base terminal of transistor 34. The frequency of oscillation of oscillator circuit O may be readily varied by altering the impedance of potentiometers 48 and 52. The output signal of the phase shift oscillator is applied through an amplifier including transistor 55 and resistor 57, and a blocking capacitor 56 to terminal 3 of alarm relay RC.

The oscillating frequency signal applied to terminal 3 of alarm relay RC is in turn applied through resonant network RN and potentiometer 60 to ground. In addition, alarm indicating devices, such as alarm bells A-1 and A-2, are coupled in parallel with each other and with resonant network RN. The frequency of oscillation is chosen so that the impedance exhibited by alarm bells A-1 and A-2 is relatively high in comparison to the impedance of variable resistor 60,

and the value of impedance of variable resistor 60 is chosen so that the impedance of resonant network RN is relatively low in comparison to the impedance exhibited by variable resistor 60. Thus, when supervisory lines L-1 and L-2 are in tact, substantially all of the output voltage developed by oscillator circuit 0 is applied across sensing potentiometer 60 thereby causing transistor 66 to become forward biased. With transistor 66 in a forward biased condition, trouble relay TR will become energized thereby preventing energization of trouble buzzer TB.

Whenever either of the supervisory lines L-1 or L-2 is disrupted, the current flowing through resonant network RN is also disrupted thereby causing substantially all of the voltage developed by oscillator circuit 0 to be applied across the alarm bells A-1 and A-2 remaining in the circuit. With substantially all of the voltage developed by oscillator circuit 0 applied across alarm bells A-1 and A-2, the voltage applied across sensing potentiometer 60 decreases to substantially zero volts, thereby reverse biasing transistor 66. Upon reverse biasing transistor 66, trouble relay TR becomes deenergized thereby energizing trouble buzzer TB. Similarly, if the disruption of lines L-1 and L-2 occurs between alarm relay RC and alarm bell A-1, the current flowing through sensing potentiometer 60 is removed, thereby causing the voltage developed across sensing potentiometer to decrease to zero volts. Again, transistor 66 becomes reverse biased thereby causing trouble buzzer TB to become energized.

Upon closure of normally open alarm actuator A, alarm relay RC becomes energized thereby causing relay armatures 5 and 6 to respectively move from relay contacts 3 and 4 to relay contacts 1 and 2. With the relay armatures in this condition, the alternating current voltage signal developed by voltage source V-1 is applied directly across alarm bells A-1 and A-2. Thus, alarm actuator A serves the function of, upon closure, energizing alarm bells A-1 and A-2. In addition, upon a disruption in the supervisory lines L-1 and L-2, trouble buzzer TB is energized thereby providing an indication of the disruption.

DESCRIPTION OF THE SECOND EMBODIMENT

Reference is now made to FIG. 2 which generally illustrates a second embodiment of the present invention which is quite similar to that illustrated in FIG. 1, accordingly, only the variations therefrom will be described in detail, and like components in both FIGURES will be identified with like character references. In accordance with this second embodiment of the invention, resonant network RN, as illustrated in FIG. 1, is replaced with a termination network TN which includes a capacitive element 80 connected in parallel with alarm bells A-1 and A-2.

The output terminal 24 of power supply circuit PS is connected through a pair of series-connected resistors 82 and 84 to ground. The junction point between resistors 82 and 84 is connected to the base of a PNP transistor 86 having its emitter connected through a resistor 87 to terminal 24 of power supply circuit PS. The emitter of transistor 86 is also connected through a capacitor 88 to terminal 24 of power supply circuit PS, and the collector of this transistor is connected through a resistor 90 to ground. Also, the collector of transistor 86 is connected through three series-connected capacitors 92, 94 and 96 to the base of this transistor. The junction point between capacitors 92 and 94 is connected through a resistor 98 to terminal 24 of power supply circuit PS, and the junction point between capacitors 94 and 96 is connected through a resistor 100 to terminal 24 of power supply PS. In addition, the collector of transistor 86 is connected through a series-connected resistor 102 and capacitor 104 to the base of an NPN transistor 106.

The base of transistor 106 is connected through a resistor 108 to terminal 24 of power supply circuit PS and through a resistor 110 to ground. Connected between the collector of transistor 106 and terminal 24 of power supply circuit PS is a

resistor 112, and connected between this collector and ground is a capacitor 114. The emitter of transistor 106 is connected through a resistor 116 to ground and is also connected to blocking capacitor 56.

Sensing network SN-1 is somewhat similar to the sensing network SN as illustrated in FIG. 1, however, potentiometer 60 is replaced with a fixed resistive element 118, resistive element 62 is deleted, a resistor 120 is connected between the base of transistor 66 and terminal 24 of power supply circuit PS, and diodes 70 and 72 are replaced with a single resistive element 122.

OPERATION OF THE SECOND EMBODIMENT

The supervisory circuit as illustrated in FIG. 2 operates in a manner substantially similar to the circuit illustrated in FIG. 1, however, a buffer stage including transistor 106 has been incorporated between the output circuit of the oscillator circuit and the alarm circuit AC-1. In addition, a single capacitive element 80 has been employed to replace the tuned resonant network RN with the net effect that the frequency of oscillation and values of circuit components are less critical. As with the supervisory circuit illustrated in FIG. 1, upon actuation of the alarm actuator A, alarm bells A-1 and A-2 are energized thereby providing an alarm indication. Similarly, upon disruption of either of the supervisory lines L-1 or L-2 the voltage developed across sensing resistor 118 decreases to substantially zero volts, thereby reverse biasing transistor 66 which, in turn, causes trouble buzzer TB to become energized. In accordance with a preferred embodiment of the invention, the values and types of various components illustrated in FIG. 1 are found in TABLE I.

Although the invention has been shown in connection with a preferred embodiment, it will be readily apparent to those skilled in the art that various changes in form and arrangement of parts may be made to suit requirements without departing from the spirit and scope of the invention.

Having thus described my invention, I claim:

1. An alarm system comprising:
a remote station monitoring circuit including actuatable means, for upon actuation, transmitting an alarm signal indicative of an alarm condition at the remote station; alarm circuit means electrically connected to said remote station monitoring circuit; said alarm circuit means including; alarm indicating means and first circuit means for energizing said alarm indicating means in response to a said alarm signal; resonant circuit means coupled to said first circuit means for normally carrying a supervisory current; and, a supervisory circuit coupled to said first circuit means and including; an oscillator circuit having second circuit means for developing an oscillating signal and third circuit means for applying a said oscillating signal to said first circuit means to thereby cause a said supervisory current to flow through said first circuit means and said resonant circuit means; means coupled to said first circuit means for developing a control signal in response to the absence of the flow of a said supervisory current resulting from a disruption in the electrical connection between the alarm circuit means and the monitoring circuit; trouble indicating means; and, signal responsive circuit means coupled to said control signal developing means for energizing said trouble indicating means in response to the receipt of a said control signal to thereby provide an indication of a disruption in the electrical connection between said alarm circuit means and the monitoring circuit. 55
2. An alarm system as set forth in claim 1 wherein said resonant circuit means is comprised of a capacitive element.
3. An alarm system as set forth in claim 2 wherein said resonant circuit means also includes an inductive element.
4. An alarm system as set forth in claim 3 wherein said capacitive and inductive elements are connected together in a series electrical configuration. 60
5. An alarm system as set forth in claim 4 wherein said series-connected capacitive and inductive elements are connected in parallel with said alarm indicating means. 65
6. An alarm system as set forth in claim 5 wherein said first circuit means includes a pair of conductors being connected across said series-connected capacitive and inductive elements.
7. An alarm system as set forth in claim 6 wherein said control signal developing means is a resistive means connected to one of said pair of conductors for developing a signal of a predetermined value with respect to ground potential in response to the flow of a said supervisory current through said first circuit means and a signal having a value substantially equal to ground potential with respect to ground potential in the absence of the flow of a said supervisory current. 75

8. In an alarm system a supervisory signal monitoring system comprising:
alarm circuit means including; alarm indicating means and first circuit means for energizing said alarm indicating means in response to the receipt of an alarm signal; and, resonant circuit means coupled to said first circuit means for normally carrying a supervisory current; and, a supervisory circuit including; an oscillator circuit having a second circuit means for developing an oscillator signal and a third circuit means electrically connecting said second circuit means to said resonant circuit means; means coupled to said third circuit means for developing a control signal in response to the absence of the flow of a said supervisory current resulting from a disruption in the electrical connection between the third circuit means and the resonant circuit means; trouble indicating means; and, signal responsive circuit means coupled to said control signal developing means for energizing said trouble indicating means in response to a said control signal developed by said signal developing means to thereby provide an indication of a disruption in the electrical connection between the third circuit means and the resonant circuit means.
9. In an alarm system as defined in claim 8 wherein said resonant circuit means is comprised of a capacitive element.
10. In an alarm system as defined in claim 9 wherein said resonant circuit means also includes an inductive element.
11. In an alarm system as defined in claim 10 wherein said capacitive element is electrically connected in series with said inductive element.
12. In an alarm system as defined in claim 11 wherein said series-connected capacitive and inductive elements are connected in parallel with said alarm indicating means.
13. An alarm system comprising:
a remote station monitoring circuit including actuatable means, for upon actuation, transmitting an alarm signal indicative of an alarm condition at the remote station; alarm circuit means electrically connected to said remote station monitoring circuit; said alarm circuit means including; alarm indicating means and first circuit means for energizing said alarm indicating means in response to a said alarm signal; capacitive means coupled to said first circuit means for normally carrying a supervisory current; and, a supervisory circuit coupled to said first circuit means and including; an oscillator circuit having second circuit means for developing an oscillating signal and third circuit means for applying a said oscillating signal to said first circuit means to thereby cause a said supervisory current to flow through said first circuit means and said capacitive means; means coupled to said first circuit means for developing a control signal in response to the absence of the flow of a said supervisory current resulting from a disruption in the said electrical connection between the alarm circuit means and the monitoring circuit; trouble indicating means; and, signal responsive circuit means coupled to said control signal developing means for energizing said trouble indicating means in response to the receipt of a said control signal from said signal developing means to thereby provide an indication of a disruption in the electrical connection between said alarm circuit means and the monitoring circuit.
14. A supervisory signal monitoring system for providing an indication of a disruption in said system and comprising:
supervisory conductor means for normally carrying a supervisory current; termination circuit means coupled to said supervisory conductor means; a trouble indicating circuit coupled to said supervisory conductor means and including;

an oscillator circuit having first circuit means for developing an oscillating signal and second circuit means for applying said oscillating signal to said supervisory conductor means to thereby cause a said supervisory current to flow through said supervisory conductor means;

means coupled to said supervisory conductor means for developing a control signal in response to the flow of a said supervisory current through said supervisory conductor means;

trouble indicating means;

signal responsive circuit means coupled to said control signal developing means for energizing said trouble indicating means in response to the absence of a said control signal to thereby provide an indication of a disruption in the supervisory conductor means.

15. A supervisory signal monitoring system as defined in claim 14 wherein said termination means is comprised of a capacitive element.

16. A supervisory signal monitoring system as defined in claim 14 wherein said termination means is comprised of an inductive element.

17. A supervisory signal monitoring system as defined in claim 14 wherein said termination means is a resonant network including a capacitive element and an inductive element.

18. A supervisory signal monitoring system as defined in 25

claim 17 wherein said capacitive and inductive elements are electrically connected in series to said supervisory conductor means.

19. A supervisory signal monitoring system as defined in claim 14 wherein said supervisory conductor means is comprised of a pair of conductors and said termination circuit means is comprised of a capacitive element connected across said pair of conductors.

20. A supervisory signal monitoring system as defined in claim 19 wherein said control signal developing means is a resistive element coupled to one of said pair of conductors, and said signal responsive circuit means includes;

15 electronic control means having an input circuit means and an output circuit means, and a first and a second condition; said input circuit means of said electronic control means being coupled to said resistive element so that upon the absence of a said control signal said electronic control means is actuated from said first condition to said second condition; and, said output circuit means of said electronic control means being coupled to said trouble indicating means to thereby energize said trouble indicating means wherever said electronic control means is actuated from said first condition to said second condition.
